UNITED STATES PATENT OFFICE

2,090,832

CHECKERWORK CONSTRUCTION

George L. Danforth, Jr., Chicago, Ill., assignor to
Open Hearth Combustion Company, Chicago,
Ill., a corporation of Delaware

Application March 2, 1936, Serial No. 66,648

2 Claims. (Cl. 263—19)

The present invention relates to improvements in checkerwork construction.

In the patent to Danforth No. 1,140,125 there is described a checkerwork construction in which the checkers are so arranged relative to one another that the upper portion of the checkerwork construction is provided with vertical channels of greater cross sectional area than are the vertical passageways between the checkers in the other portions of the checkerwork, whereby communication is provided between adjacent channels and the advantage is attained that to a large extent the congestion due to deposition of solid products of combustion is reduced. In the patent to Peterson No. 1,687,786 there is described a checkerwork construction in which the side slipping of the checkers is minimized.

An object of the present invention is to provide a checkerwork construction having great stability, great storage capacity for heat, and large exposed surface for taking the heat into and out of storage, which construction is relatively cheap to install and to maintain.

A further object is to provide a checkerwork construction having the advantages above referred to and which in very considerable part uses checkers which are simple in design.

A further object is to provide an improved checkerwork construction in which a very large proportion of the checkers may remain in position for a number of campaigns, thereby reducing the cost of purchasing brick and also the cost of removal and the relaying of such brick.

A further object is to provide a checkerwork construction well adapted to meet the needs of commercial operation.

Further objects will appear as the description proceeds.

Referring to the drawings—

Figure 1 is a longitudinal section through a checkerwork construction embodying the principles of the present invention;

Figure 2 is a vertical section taken along the plane indicated by the arrows 2—2 of Figure 1;

Figure 3 is a diagrammatic view taken along the plane indicated by the arrows 3—3 of Figure 2, illustration of the individual checkers being omitted, showing the positions of the wells as contemplated in the present invention;

Figure 4 shows in fragmentary sections views taken along the planes indicated by the stepped section line indicated by the arrows 4—4 of Figure 2;

Figure 5 is a view on an enlarged scale of a por-

tion of the checker construction shown in Figure 1;

Figure 6 is a corresponding fragmentary view taken along the plane indicated by the numerals 6—6 of Figure 5;

Figure 7 is a view on an enlarged scale of another portion of the checker construction shown in Figure 1;

Figure 8 is a corresponding fragmentary view taken along the plane indicated by the numerals 8—8 of Figure 7;

Figures 9, 10 and 11 show the arrangement of the checkers in three of the courses illustrated in Figures 7 and 8; and

Figure 12 is a view of a checker such as disclosed in the Peterson Patent No. 1,687,786 above referred to, and such as may be used, if preferred, in the practice of the present invention.

Referring to Figures 1 to 4, a portion of a regenerator 10 is illustrated having the side walls 11—11, the bottom 12, the top wall 13 and the end walls 14—14. The regenerator 10 has the conventional passageways 14a—14a for the passage of air and gas. Disposed lengthwise of the regenerator 10 are the foundation piers 15 which are adapted to support the checkerwork within said regenerator 10. Said piers 15—15 may be stepped in height longitudinally, as shown in Figure 1, three steps being illustrated, indicated by the numerals 15a, 15b and 15c. Disposed in arched relationship transversely between adjacent piers 15 and the side walls 11—11 are the arches 16—16. Said arches 16—16 are built up to have flat tops as shown in Figure 2 to facilitate their checker supporting functions, and the dimension of each of said arches is preferably narrow in a direction longitudinally of the regenerator. Said arches are, of course, spaced apart longitudinally of said regenerator. In order to have ample working room between the piers 15—15, the arches 16 should be of considerable length. By reason of the fact that their dimensions longitudinally of the regenerator are limited, it will be found necessary to rigidly hold said arches 16 in position. For this purpose a plurality of series of foundation blocks are provided, which foundation blocks are indicated by the numerals 17—17. Said foundation blocks 17—17 are deeply notched on their lower edges whereby to provide the long legs 17a and the shoulders 17b—17b. Said long legs 17a are adapted to lie between the adjacent arches 16 and said shoulders 17b—17b are adapted to rest upon the tops of said arches 16. Said legs 17a provide side bearings for the arches 16 (at the

center portions of said arches) throughout the greater part of the vertical dimension of said arches. The head portions of said foundation blocks 17-17 are adapted to substantially abut longitudinally of the regenerator as shown in Figure 1 and are arranged in parallel files extending longitudinally of the regenerator, which files are spaced apart transversely of said regenerator. The foundation blocks disposed at the junctures of the steps 15a, 15b and 15c are of slightly different contour than the other foundation blocks. The leg portion of each of the foundation blocks just referred to is longer than the corresponding leg portion of the other foundation blocks and is provided with a shoulder portion 18. The bottom of each shoulder portion 18 is adapted to rest upon an arch 16, and the upper surface of each shoulder portion 18 is adapted to line up with the upper surface of the adjacent foundation blocks 17-17.

The construction and arrangement of foundation blocks 17-17 produce a plurality of steps of flat bearing surfaces indicated by the numerals 19, 20 and 21. The spaced apart parallel files of foundation blocks 17-17 provide longitudinally extending channels 22-22 communicating with the longitudinal passages provided by the foundation piers 15-15.

Carried by the foundation blocks 17-17 is an assembly of checkers 23-23. The design of the checkers 23-23 forms no part of the present invention, but preferably said checkers should be so designed that the liability of slipping thereof in service is minimized. It is at present preferred to use the type of checker disclosed and claimed in the Peterson Patent No. 1,687,786, which checker is illustrated in the figures of the drawings accompanying this specification, particularly in Figure 12 thereof. It will be understood, however, that the invention is not limited to the particular checker illustrated.

The top part of the checkerwork of a regenerator receives the greatest amount of punishment from the hot gases, and a construction is contemplated in which it will be necessary to renew only this portion of the checkerwork after the destructive effect of a furnace campaign. Accordingly, the assembly of the checkerbricks 23-23 extends up to a plane indicated in Figure 1 by the numeral 24. This plane 24 is chosen at a level below which the destructive effects of the hot gases are not so great as to require frequent replacement. The checkerbrick (including the foundation blocks 17-17) below the plane 24 will, in service, amount to about 70 per cent of the total checker construction in the regenerator 10. The removal of checkers above the plane 24 will give ample working space to clean the checkerwork therebelow by the use of compressed air or by lancing or any other method commonly used. There is ample space below the remaining checkerwork, that is—in the space below the arches 16-16, to permit the removal of dust which settles in this space while the furnace is in operation and which settles therein due to the cleaning of the checkerwork thereabove.

The present invention contemplates the utilization above the plane 24 of checkers laid on edge of standard dimensions and shape, or of checkers of conventional shape and close to standard dimensions, whereby the cost of said checkers is low. To this end, the checkers in the regenerator above the surface 24 are right parallelopipeds, or, in other words, they are bricks with no special 75 notches or deformation of any kind, so that they

can be used for second-hand purposes when not good enough for re-use for regenerative purposes.

In carrying out the present invention in the construction of the regenerator above the surface 24, it is proposed to use checkerbricks of two sizes. It is at present preferred to use a supply of standard bricks of dimensions of $9 \times 4\frac{1}{2} \times 2\frac{1}{2}$ inches and a lesser number of other bricks of substantially $10\frac{1}{4} \times 4\frac{1}{2} \times 2\frac{1}{2}$ inches. In other words, the present invention contemplates the use of standard size bricks supplemented by other bricks of standard thickness and width and exceeding the length of standard bricks only by half the thickness of a standard brick.

According to the present invention, wells are provided in the checker construction above the surface 24, and communication is provided between said wells, so that even though some of the vertical passages entering the checkerwork are obstructed by flue dust or other deposit, communication to the upper portion of the regenerator will be provided through said wells and through unobstructed transverse passageways. The present invention contemplates an improvement over the idea of the Danforth Patent No. 1,140,125. The wells referred to are indicated by the numerals 25-25.

Referring to Figure 1, there is disposed above the surface 24 a layer of checkers 26-26, which form a course indicated by the letter C (Figs. 1, 2, 7, 8 and 11). In the illustrated embodiment of the present invention the checkers in the course C are of standard dimensions, to wit— $9 \times 4\frac{1}{2} \times 2\frac{1}{2}$ inches. As indicated, the checkers in the course C are disposed in parallel files and provide channels extending transversely of the regenerator 10. Disposed above the course C is the course B (Figs. 1, 2, 7, 8 and 9). The checkers in course B will also be of standard size and are indicated by the numerals 26-26. The checkers in course B are disposed in parallel files extending crosswise with respect to the checkers of course C, with their end faces lying midway of the thickness of the checkers of course C (Fig. 7). It will be understood, of course, that for the purpose of filling out the space within the walls of the regenerators, some of the longer checkers may be used. These longer checkers are indicated by the numerals 27-27 and according to the illustration above given may have dimensions of $10\frac{1}{4} \times 4\frac{1}{2} \times 2\frac{1}{2}$ inches. Alternating with courses B-B at the region of the wells 25-25 are courses A-A (Figs. 1, 2, 7 and 8) made up of the long checkers 27-27 and standard checkers 26-26. The checkers in courses A-A are disposed in parallel files, and between certain of the files of checkers 26-26 of each course A are files of checkers 27, which are laid in pairs, end to end, adjacent pairs being spaced apart at the wells 25. As clearly shown in Figure 8, each pair of checkers 27-27 provides full bearing for three crosswise extending checkers 26-26.

The upper levels of the checkers within the regenerator may be stepped in correspondence with the steps 15a, 15b and 15c of the supporting piers 15, and the wells 25-25 may extend downwardly from the top course of checkers to any preferred extent. According to the present invention, each well 25 is vertically aligned with at least two passageways defined by the checkerbricks 23-23.

At first glance it might appear that the arrangement of checkerbrick above the surface 24 as immediately above described would produce a rather unstable assembly. However, the wells 75

25, which are useful in providing passageways for gas even though there is a tendency for certain of the passageways to be clogged with dust or other foreign matter, promote a useful co-operation between the standard bricks 26 and the longer bricks 27. As mentioned above, the preferred dimensions of the bricks 27-27 are $10\frac{1}{4} \times 4\frac{1}{2} \times 2\frac{1}{2}$ inches, whereas the bricks 26-26 measure $9 \times 4\frac{1}{2} \times 2\frac{1}{2}$ inches. In other words, 10 the longer bricks exceed the length of the standard bricks to an extent equal to one-half of the thickness of the bricks 26 or 27. As will be clear from an inspection of Figure 8, courses of bricks 27-27 interposed between courses of bricks 15 26-26 produce the advantage that two bricks 27-27 placed end for end provide an excellent bearing for the bricks 26-26 superimposed thereupon. As will be clear from Figure 8, two bricks 27-27 placed end for end provide a full 20 2 $\frac{1}{2}$ inch bearing for each of the two bricks at the two ends of such a pair. At the juncture of the two bricks 27-27 of such an assembly, a full bearing is provided for a brick 26 disposed immediately thereabove. The result is achieved, 25 therefore, that by the provision of the wells 25-25 the elongated bricks cooperate with the standard size bricks to provide excellent bearing surfaces for the bricks in the upper section of the checker assembly.

30 The uppermost course of checkerbricks may be of the type which interlock with the other bricks 26 or 27 to prevent side slip.

It will be noted that the longitudinal center lines of the arches 16-16 have the same spacing 35 as the longitudinal center lines of the parallel rows of checkerbrick extending transversely of the regenerator. In other words, the longitudinal center lines of the arches are in vertical alignment with the longitudinal center lines of the transversely extending rows of checkerbrick. 40 Therefore, the multiplicity of arches and the foundation blocks carried thereby, with their long legs 17a, provide a stable structure having a very large amount of exposed surface for regenerator purposes.

By reason of the construction illustrated and described, the bricks in the upper portion of the checkerwork assembly, illustrated as being about 30 per cent of the bricks in said assembly, are 45 for the most part of standard size and may be purchased at relatively low cost. In order to achieve the results and advantages of the wells 25-25, checkerbricks are utilized differing only slightly from standard brick in length and in cost, and the advantage is achieved that excellent bearing surfaces are provided in the upper portion of the checkerwork assembly, whereby sturdiness is had without recourse to high-priced special checker constructions. Inasmuch 50 as the bricks are laid on edge, the horizontal passages have a vertical dimension equal to the width of the brick; that is, considering the example above given, said horizontal passages have a vertical dimension of $4\frac{1}{2}$ inches. The horizontal 55 passages have a horizontal dimension of $6\frac{1}{2}$ inches.

By reason of the fact that each of the interlocking checkerbricks 23-23 has a portion extending down between the checkerbricks of the course therebelow, the ratio between the cross-sectional area of the horizontal transverse passageways and the corresponding cross-sectional area of the material of the checkerbricks 26-26 is less than the corresponding ratio between the cross-sectional area of the horizontal passageways defined by the parallelopiped checkerbricks 26-26-27-27 and the cross-sectional area of said checkerbricks. In other words, in the upper part of the checkerbrick assembly, the area for the passage of air or gas horizontally of the assembly is greater relative to the material 10 of the checkerbricks than is the corresponding area in the lower portion of the assembly. 15

Though a certain preferred embodiment of the present invention has been described in detail, many modifications will occur to those skilled in the art. It is intended to cover all such modifications that fall within the scope of the appended claims.

What is claimed is—

1. A checkerbrick assembly including courses of parallel files of checkerbricks, each of said bricks being a right parallelopiped, some of said bricks being of one size and shape, the others of said bricks exceeding said first mentioned bricks in length an amount equal to one-half the thickness of said first mentioned bricks, the files in alternate courses being disposed crosswise to provide vertical passageways, said assembly at the upper region thereof being provided with vertical wells each communicating vertically with a plurality of said passageways, certain of said longer bricks being spaced apart longitudinally to provide said wells, the end faces of certain of said longer bricks and the side faces of certain of said first mentioned 30 bricks defining smooth side walls of said wells, said bricks being disposed with their widths vertical. 35

2. A checkerbrick assembly including a lower portion composed of notched checkerbricks interlocked with one another to prevent slip, the upper portion of said assembly being right parallelopipeds, some of said parallelopipeds being of one size and shape, the others of said parallelopipeds exceeding said first-mentioned parallelopipeds in length an amount equal to one-half the thickness of said first-mentioned parallelopipeds, the files in alternate courses being disposed crosswise to provide vertical passageways, said assembly at the upper region thereof being 40 provided with vertical wells each communicating vertically with a plurality of said passageways, certain of said longer parallelopipeds being spaced apart longitudinally to provide said wells, the end faces of certain of said longer parallelopipeds and the side faces of certain of said first mentioned parallelopipeds defining smooth side walls of said wells, said parallelopipeds being disposed with their widths vertical. 45
